UNITED STATES PATENT OFFICE.

JOHN A. BUCHANAN, OF PITTSBURG, PENNSYLVANIA.

SWINGLETREE.

No. 809,769.

Specification of Letters Patent.

Patented Jan. 9, 1906.

Application filed November 10, 1904. Serial No. 232,189.

To all whom it may concern:

Be it known that I, JOHN A. BUCHANAN, a citizen of the United States, residing at Pittsburgh, in the county of Allegheny and State of Pennsylvania, have invented or discovered certain new and useful Improvements in Swingletrees, &c., of which improvements the following is a specification.

The invention described herein relates to certain improvements in swingletrees, double-trees, neck-yokes, &c., and these several devices will hereinafter be referred to generically as "trees."

The invention has for its object a construction in which the body of the article is formed of metal sheets so bent as to present an efficient resistance both horizontally and vertically.

The invention is hereinafter more fully described and claimed.

In the accompanying drawings, forming a part of this specification, Figure 1 is a plan view of my improved swingletree, &c. Figs. 2 and 3 are transverse sections on planes indicated, respectively, by the lines II II and III III, Fig. 1.

In the practice of my invention the body 1 of the article is formed of a single sheet of metal bent to substantially tubular form in cross-section. The sheet from which the body is formed is preferably made tapering from points adjacent to but on opposite sides of the middle of the blank toward both ends, so that the body when formed by bending the sheet longitudinally will be similarly tapered. The edges of the sheet are so-bent that when the sheet has been bent to tubular form these edges will form inwardly-projecting radial flanges 2, which will present a highly efficient brace along the rear wall of the body, as against horizontal transverse bending strains. The front wall of the body of the article is strengthened as against horizontal and vertical transverse strains by a series of longitudinal ribs 3 and 4, projecting alternately in opposite directions, as clearly shown in Figs. 2 and 3. These ribs are conveniently formed by longitudinally corrugating or oppositely bending the middle portion of the sheet either before it is bent to tubular form or while bending the sheet to such form.

The body is held in its tubular form, with the flanges 2 bearing one against the other, by the clips or fittings, which are preferably formed of malleable cast-iron. The middle

fitting 5 is provided on its ends with lugs 6, through which pass the bolts or rivets, whereby the fitting is clamped around the body, and with lugs 7, having holes or openings 8 for the reception of suitable connecting members or parts. The end fittings or clips consist of straps 9, bent around the ends of the body and provided with lugs or ears 10, through which pass rivets or bolts securing the straps in position. The parts or members 11, to which the traces, &c., are connected, are U or staple shape, having at their ends laterally-extending lugs 12, forming journals for the U or staple shaped members. These lugs or journals are arranged in the longitudinal groove between the strengthening-ribs 3 and are held in position by the straps, which form bearings for the journals. It is preferred that these journals should extend outwardly, as shown, and in such case a slot or opening is formed in the strap to permit of the passage of the body of the U-shaped member when applying it to the body 1 of the article. This construction permits the easy renewal of the U-shaped part or member, which is worn out rapidly in use.

The sides, especially the under side of the middle fitting or clip, are made thick and flat, as it forms a bearing when the swingletree or doubletree is secured in position by a pin 13, as shown. When such pin is employed, the lugs or ears 7 may be omitted.

I claim herein as my invention—

1. A tree or means for attaching horses to wagons, having along one edge inwardly-projecting flanges and with ribs along its opposite edge, said ribs projecting alternately in opposite directions, substantially as set forth.

2. A hollow tree or means for attaching horses to wagons having flat or approximately flat sides and provided with ribs along one edge in combination with an attaching U-shaped part or member provided with journals projecting between adjacent ribs on the tree and a strap surrounding the tree and provided with bearings for said journals, substantially as set forth.

3. A hollow tree or means for attaching horses to wagons having flat or approximately flat sides and provided with ribs along one edge in combination with an attaching U-shaped part or member having outwardly-projecting journals projecting between adjacent ribs on the tree and a strap surrounding the tree and provided with bearings for said

journals and having an opening or slot for the projection of the body or U-shaped part therethrough, substantially as set forth.

4. A tree or means for attaching horses to wagons having a groove along its front edge, a slotted strap surrounding the tree, a U-shaped part or member projecting through the slot in the strap and having journals arranged in the groove in the tree and bearing on the portions of the strap forming the sides of the slot, substantially as set forth.

5. A hollow tree or means for attaching

horses to wagons having flat or approximately flat sides, and provided along one edge with a series of longitudinal ribs projecting alternately in opposite directions, the outer walls of the outer ribs being in the planes of the flat sides of the tree. 15

In testimony whereof I have hereunto set my hand.

JOHN A. BUCHANAN.

Correction in Letters Patent No. 809,769.

It is hereby certified that in Letters Patent No. 809,769, granted January 9, 1906, upon the application of John A. Buchanan, of Pittsburgh, Pennsylvania, the title of the invention should read *Singletree* instead of "Swingletree," and wherever the word "Swingletree" appears throughout the specification it should be read *Singletree*; and that the said Letters Patent should be read with this correction therein that the same may conform to the record of the case in the Patent Office.

Signed and sealed this 30th day of January, A. D., 1906.

journals and having an opening or slot for the projection of the body or U-shaped part therethrough, substantially as set forth.

4. A tree or means for attaching horses to wagons having a groove along its front edge, a slotted strap surrounding the tree, a U-shaped part or member projecting through the slot in the strap and having journals arranged in the groove in the tree and bearing on the portions of the strap forming the sides of the slot, substantially as set forth.

5. A hollow tree or means for attaching

horses to wagons having flat or approximately flat sides, and provided along one edge with a series of longitudinal ribs projecting alternately in opposite directions, the outer walls of the outer ribs being in the planes of the flat sides of the tree. 15

In testimony whereof I have hereunto set my hand.
